(57) **CLAIM**

The ornamental design for an electrical outlet, as shown and described.

DESCRIPTION

FIG. 1 is a front perspective view of a first embodiment of the electrical outlet; according to our new design;

FIG. 2 is a front exploded perspective view of the electrical outlet of FIG. 1;

FIG. 3 is a rear perspective view of the electrical outlet of FIG. 1;

FIG. 4 is a rear exploded perspective view of the electrical outlet of FIG. 1;

FIG. 5 is a rear view of the electrical outlet of FIG. 1;

FIG. 6 is a right side view of the electrical outlet of FIG. 1;
FIG. 7 is a ride side exploded view of the electrical outlet of FIG. 1;

FIG. 8 is a left side view of the electrical outlet of FIG. 1;

FIG. 9 is a left side exploded view of the electrical outlet of FIG. 1;

FIG. 10 is a top view of the electrical outlet of FIG. 1;

FIG. 11 is a top exploded view of the electrical outlet of FIG. 1;

FIG. 12 is a bottom view of the electrical outlet of FIG. 1;
FIG. 13 is a bottom exploded view of the electrical outlet of FIG. 1;

FIG. 14 is a front view of the electrical outlet of FIG. 1;

FIG. 15 is a front view of a second embodiment of the electrical outlet; according to our new design; and,

FIG. 16 is a front view of a third embodiment of the electrical outlet specific to NEMA 5 connectors; according to our new design.

In FIG. 15, the stippling is intended to show a difference in appearance. In FIGS. 1-15, the broken lines are for the purpose of illustrating environment only and form no part of the claimed design. Although certain figures are shown with an exploded view, the electrical outlet may be formed as a single piece without separate, unconnected parts. Also, although certain figures are shown with a specific surface texture, any surface texture may be utilized on the left side ornamental feature as appropriate for specific applications in different embodiments.
